CLAIM

The ornamental design for a mat with body portion, as shown and described.

DESCRIPTION

This Design Patent Application is also related to U.S. Design Pat. No. Des. 426,415, entitled "Towel with Pillow," filed May 27, 1999; and U.S. Design Pat. No. D449,193, entitled "Mat with Pillow," filed Feb. 6, 2001; and U.S. Design Pat. No. D447,661, entitled "Mat with Inflatable Pillow," filed Feb. 6, 2001; and U.S. Design Pat. No. D459,934, entitled "Mat with Pillow and Body Portion," filed Jun. 13, 2001; and U.S. Design Pat. No. D463,700, entitled "Mat with Pillow Portion and Body Portion," filed Aug. 14, 2001; and U.S. Design Pat. No. D596,438, entitled "Mat with Body Portion," filed Jul. 28, 2008; the disclosures of all of which are incorporated herein by reference.

FIG. 1 is a top view of a mat with body portion according to an embodiment;

FIG. 2 is a left side view of the mat with body portion illustrated in FIG. 1, the right side view being a mirror image of the left side view;

FIG. 3 is a bottom view of the mat with body portion illustrated in FIG. 1; and,

FIG. 4 is a front end view of the mat with body portion illustrated in FIG. 1.

The broken lines immediately adjacent the shaded areas represent the bounds of the claimed design while all other broken lines are directed to environment and are for illustrative purposes only; the broken lines form no part of the claimed design.
